BURIAL VAULT

Claude R. Neff, Camden, Ohio, assignor to The
Neff & Fry Company, Camden, Ohio, a corpora-
tion of Ohio

Application March 13, 1937, Serial No. 130,617

8 Claims. (Cl. 72—7)

My invention relates to burial vaults. It has to do, more particularly, with that type of burial vault known as a surface burial vault and which has its top surface substantially flush with the surface of the earth.

One of the objects of my invention is to provide a surface burial vault which includes a casket chamber and which is of such a nature that the casket chamber may be horizontally disposed and the top surface of the vault will lie flush with the surrounding surface of the earth regardless of the inclination or grade of such surface.

Another object of my invention is to provide a burial vault of the type indicated which is provided with means for absorbing moisture emitted by the corpse.

Another object of my invention is to provide a surface burial vault which is made up of a plurality of units and which is provided with means for effectively sealing the units.

In its preferred form my invention contemplates the provision of a vault which consists of a main body portion adapted to form the casket chamber. A lid is provided for covering the upper end of the casket chamber and the lid is sealed theron by a dual seal consisting of an air seal and a seal comprising some suitable sealing composition. On the upper surface of the lid I preferably provide an upwardly projecting continuous flange which serves to provide a receptacle for some suitable absorbent material which will absorb the moisture emitted by the corpse in the casket chamber and which escapes through the said lid. The absorbent material preferably extends over the entire casket chamber. I provide a second unit embodying an upper slab having a depending continuous flange which fits on the outside of the upwardly projecting flange formed on the lid of the casket chamber. A dual seal is also provided between this unit and the lid of the casket chamber. This unit serves to form a dead air insulating chamber above the casket chamber.

The burial vault is so constructed that the casket chamber may be horizontally disposed and the slab at the top of the second unit may be disposed at any desired angle so that it will conform to the grade of the surface of the earth surrounding it. If the grade is inclined, the top slab may be disposed in a correspondingly inclined position. This may be accomplished by having the upstanding flange on the lid substantially wedge-shaped, or in other words, projecting from the lid a gradually increasing distance from one end thereof to the other, in order that the

top slab will be in the desired angular relationship to the lid of the casket chamber and, consequently, correspond to the inclination of the grade of the surrounding surface. The same result may be accomplished by having the depending flange on the top unit wedge-shaped instead of having the upstanding flange on the lid so shaped.

The preferred embodiment of my invention is illustrated in the accompanying drawings where-in similar characters of reference designate corresponding parts and wherein:

Figure 1 is a perspective view, partly broken away, showing a burial vault made according to my invention in position in the earth and illustrating how the top slab thereof may be disposed at the same inclination as the surrounding surface of the earth.

Figure 2 is a longitudinal section taken through the vault illustrated in Figure 1.

Figure 3 is a view similar to Figure 1 but showing different means for obtaining the proper inclination of the top slab.

Figure 4 is a longitudinal section taken through the vault illustrated in Figure 3.

Figure 5 is a detail in section illustrating the seal provided between the casket chamber and the lid and between the lid and the top unit.

Figure 6 is a view similar to Figure 4 but showing the top slab horizontally disposed and parallel to the lid of the casket chamber.

With reference to the drawings, I have shown a surface burial vault made in accordance with my invention. This vault may be constructed of any suitable material, preferably cast-stone or concrete, although it may be made of various plastic or other materials. Although I have not shown the material reinforced, it will be understood that it may be reinforced in a suitable manner.

The vault comprises a body portion 1, which is adapted to form a chamber 2 in which the casket is adapted to be placed. It will be noted that the body portion 1 is of substantially box-like form. The chamber 2 may be of any suitable size and is preferably of such a size as to receive several different sizes of caskets. If desired, the inner surface of the bottom of the casket chamber may be provided with suitable supports on which the casket will rest.

A lid 3 is provided for closing the upper end of the casket chamber 2. This lid comprises a flat slab-like portion adapted to extend over the entire upper end of the casket chamber and to cover such chamber. This slab-like portion is

provided with a continuous flange 4 which depends therefrom a considerable distance. It will be obvious that when the lid 3 is positioned on the upper end of the body portion 1 a space 5 (Figure 2) is formed between the inner surface of the flange 4 and the outer surface of the upper end of the walls of the body portion 1. Before the lid 3 is placed on the upper end of the body portion 1, suitable sealing material 6 10 is preferably placed entirely around the upper edge of such body portion in order to make the chamber 2 substantially air-tight.

It will be understood that when the lid 3 is mounted on the upper end of the body portion 1, 15 the casket chamber 2 will be effectively sealed by a dual seal. If water begins to ascend into the space 5 it will compress the air therein and, therefore, further movement of the water upwardly will be precluded. If no sealing compound were used between the lid 3 and the body portion 1, movement of water up into the space 5 would compress the air in such space and in the casket chamber itself so that further movement of the water would be precluded. In other words, the lid 3 in cooperation with the body portion 1 forms an air seal which will prevent entrance of water into the casket chamber.

The sealing compound 6 when used will also aid in preventing moisture from entering the casket chamber 2 and will preclude the passage of air thereinto. Therefore, it is desirable to use the sealing compound. By sealing the lid 3 to the body portion 1 with a suitable compound, these units will be so bound together that they 35 will practically be the same as one unit.

The upper surface of the lid 3 is provided with an upwardly projecting continuous wall 7. It will be noted from Figures 1 and 2 that this wall 7 extends along all of the peripheral edges of 40 the lid 3. It will also be noted that the wall 7 gradually increases in height from one end of the lid to the other. At the left hand end of the lid 3 (Figure 2) the height of the wall 7 is substantially negligible while at the right hand 45 end of the lid its height is a maximum. Thus, the top edge of the wall 7 will be inclined from one end of the wall to the other. The wall 7 has a flange 8 formed at its upper edge and has an inclined shoulder 9 formed thereon outside 50 of the flange 8.

I have provided a top cover unit 10 which includes a top slab-like portion 11 having an integral continuous depending peripheral flange 12. This top cover unit 10 is adapted to be placed 55 in cooperative relation with the unit 3 in such a manner that the flange 12 of the unit 10 will lie outside of the flange 8 of wall 7 of unit 3. The lower edge of the flange 12 will substantially contact with the shoulder 9 while the upper edge 60 of the flange 8 will substantially contact with the inner surface of the slab-like portion 11. It will be noted that the flange 12 is perpendicular to the slab-portion 11 of unit 10 but that the flange 8 is at an angle to lid 3 in order that 65 flange 8 will be parallel to flange 12 even though the top unit 10 is in inclined position, as indicated. The flanges 8 and 12 will be in slightly spaced relationship so that a space 13 will be formed therebetween.

70 Thus, it will be noted that since the flanges 8 and 12 are arranged as indicated, an air-seal will be produced between these two flanges and, consequently, there will be no danger of water entering the chamber formed between the top 75 cover unit 10 and the unit 3. Sealing material

14 is preferably placed between the lower edge of flange 12 and the shoulder 9 and between the upper edge of flange 8 and the inner surface of slab-like portion 11 in order to prevent entrance of air into the chamber formed between unit 10 and unit 3 and in order to firmly bind the top unit 10 to the unit 3. A suitable marker 15 may be provided on the upper surface of the slab-like portion 11 of the unit 10, as indicated.

It will be noted that the slab-like portion 11 10 will be inclined relative to the lid 3. It is desirable to have it inclined to a predetermined extent when the vault is to be placed in a grave where the surrounding earth's surface is at an 15 inclination. The unit 10 is so mounted on the unit 3 that an insulating chamber is formed which is substantially wedge-shaped in vertical longitudinal section. The inclination of the slab-like portion 11 may be varied by varying the inclination of the upper edge of the combined 20 flange 8 and wall 7 to suit any terrain in which the vault is to be embedded.

The wall 7 which projects upwardly from the lid 3 also serves to form a receptacle on top of the lid in which a layer of a suitable absorbent 25 material 16 may be disposed. This absorbent material is adapted to absorb moisture emitted from the corpse and which will pass upwardly through the lid 3 which is made sufficiently porous to permit this. It will be noted that the 30 layer of material 16 will cover substantially the entire casket chamber. This material is preferably a loose layer of powdered gypsum although it may be any other suitable material which will absorb the moisture. This layer of material will 35 also serve to insulate the casket chamber.

In positioning this vault in the earth, the body portion 1 is first placed in the grave. It is desirable for this body portion to be horizontally disposed regardless of the inclination or grade 40 of the top surface of the surrounding earth. The casket is then lowered into the casket chamber. The lid 3 is then positioned on the upper end of the casket chamber. Then the material 16 is positioned on top of the lid within the wall 7. 45 The top cover unit 10 is then placed on the unit 3 with its flange 12 surrounding the flange 8 of unit 3. Material is then filled in around the vault. The inclination of the top edge of the flange 8 should be such that the slab-like portion 11 of unit 10 will lie substantially flush 50 with the surface of the surrounding earth. The inclination of the flange 8 may be predetermined so that it will correspond to the inclination or grade of the surface in which the vault is to be 55 embedded. The wall 7 and the flange 8 thereof may be so formed as to dispose the slab-like portion 11 of the unit 10 at any desired angle relative to the unit 3.

In Figures 3, 4 and 5, I show different means for 60 obtaining the proper inclination of the top slab of the unit 10a. In this case, instead of the upstanding flange on the lid 3a being inclined from one end of the vault to the other the depending flange on the top unit 10a is so inclined. Thus, 65 flange 8a on lid 3a, corresponding to flange 8, projects from the lid a uniform distance throughout its length. However, flange 12a, corresponding to flange 12, depends from the slab-like portion 11a a gradually increasing distance from one end of 70 the slab to the other. In this case, the flanges 12a and 8a, as illustrated in Figure 5, will form an air seal in the same manner that the flanges 12 and 8 form an air seal. However, in this instance the flange 12a will rest on the top surface of the lid 3a 75

and this will be the only point where the sealing material 14 will be placed. Any water tending to flow up through the space 13a, formed between flanges 8a and 12a, will compress the air in said space and in the insulating chamber and further movement of the water into said space will be precluded.

If desired, a cover slab 17 may be made separate from slab 11a and may be placed thereover and secured thereto in a suitable manner.

In Figure 6 I illustrate a burial vault which is constructed exactly as the burial vault illustrated in the other figures with the exception that the top slab 11b is parallel to the lid 3b. In this case, 15 each of the flanges 8b and 12b will be made the same dimensions throughout its entire length. This burial vault will be used when the surface of the surrounding earth is substantially level.

The insulating chamber above the lid will form 20 a very effective insulating means between the outside air and the casket chamber 2. Furthermore, this insulating action will be enhanced by the layer of material 16. Thus, an even temperature will be maintained in the casket chamber and the 25 casket cannot be affected to any appreciable extent by outer air conditions and, consequently, deterioration of the corpse will be delayed. The action of the sun or warmth upon the exposed part of the burial vault, due to capillary attraction, 30 tends to draw any moisture in the casket chamber 2 from such chamber through the lid 3 and into the layer of material 16 which will absorb it. Thus, since no moisture can enter the casket chamber 2, the moisture contained in the body 35 itself will be eventually extracted and absorbed, thereby eliminating disintegration.

It will be apparent that this vault is made of three sections, viz., the body portion 1, the lid 3 and the unit 10. Since the vault is constructed in 40 this manner, it may be readily handled and positioned in the grave.

From the preceding description and the following claims, it will be apparent that the burial vault which I have provided has many important 45 advantages.

Having thus described my invention, what I claim is:

1. A burial vault comprising a hollow body portion adapted to form a casket chamber, a lid 50 mounted upon the upper end of said casket chamber, said lid having an upwardly projecting continuous flange, a top unit adapted to be disposed above said lid, said unit embodying a top member having a depending continuous flange, 55 the depending flange of the top unit being disposed adjacent to and on the outside of the upwardly projecting flange of the lid and in cooperative relationship therewith so as to produce an air-seal between said flanges.

2. A burial vault comprising a hollow body portion adapted to form a casket chamber, a lid 60 mounted upon the upper end of said casket chamber, said lid having an upwardly projecting continuous flange, a top unit adapted to be disposed above said lid, said unit embodying a top member having a depending continuous flange, the depending flange of the top unit being disposed 65 adjacent to the upwardly projecting flange of the

lid and in cooperative relationship therewith in order to produce an air seal between said flanges.

3. A burial vault comprising a hollow body portion adapted to form a casket chamber, a lid 5 mounted upon the upper end of said casket chamber, said lid being provided with a continuous depending flange adapted to form an air seal between said lid and said body portion, a top unit adapted to be disposed above said lid, said unit embodying a top member having a depending continuous flange, said lid also having an upstanding continuous flange, the depending flange of the top unit being disposed adjacent to the upstanding flange of the lid and in cooperative relationship therewith in order to produce an air seal between 15 said flanges.

4. A burial vault comprising a hollow body portion adapted to form a casket chamber and having the top thereof open, a lid mounted on the top of said body portion, said lid having an upstanding continuous flange, said flange projecting from one end thereof to the other, and a top portion cooperating with said flange so that it will be disposed at an angle to the lid of the body portion. 20

5. A burial vault comprising a hollow body portion adapted to form a casket chamber and having the top thereof closed, a hollow member mounted on the top of said body portion, said member comprising a top portion having a continuous depending flange, said flange being of gradually increasing 30 depth from one end of the top portion to the other so that the said top portion will be at an angle to the top of the casket chamber.

6. A burial vault comprising a hollow body 35 portion adapted to form a casket chamber having the top thereof closed, a hollow member mounted on the top of said body portion, said hollow member having its top closed and being substantially wedge-shaped in vertical longitudinal cross- 40 section.

7. A burial vault comprising a hollow body portion adapted to form a casket chamber, a lid mounted upon the upper end of said casket chamber, said lid having an upwardly projecting continuous flange, said flange projecting from the lid 45 gradually increasing distances from one end thereof to the other, a top unit adapted to be disposed above said lid, said unit embodying a top member having a depending continuous flange, 50 the depending flange of the top unit being disposed adjacent to the upwardly projecting flange of the lid and in cooperative relationship therewith in order to produce an air-seal between said flanges. 55

8. A burial vault comprising a hollow body portion adapted to form a casket chamber, a lid mounted upon the upper end of said casket chamber, said lid having an upwardly projecting continuous flange, a top unit adapted to be disposed 60 above said lid, said unit embodying a top member having a depending continuous flange, said depending flange being of gradually increasing depth from one end of the top member to the other, said depending flange of the top unit being disposed 65 adjacent to the upwardly projecting flange of the lid and in cooperative relationship therewith in order to produce an air-seal between said flanges.

CLAUDE R. NEFF.
